[57] CLAIM

The ornamental design for a woven cloth basket, as shown.

DESCRIPTION

FIG. 1 is a top perspective view of a woven cloth basket
showing my new design;
FIG. 2 is a front elevational view;
FIG. 3 is a top plan view;
FIG. 4 is an end elevational view, the opposite end
being a mirror image thereof;
FIG. 5 is a rear elevational view; and
FIG. 6 is a bottom plan view.
